UNITED STATES PATENT OFFICE.

GEORGE C. ANTHON, OF NEW YORK, N. Y., ASSIGNOR TO STANLEY INSULATING COMPANY, OF GREAT BARRINGTON, MASSACHUSETTS, A CORPORATION OF MAINE.

HEAT-INSULATED RECEPTACLE.

Application filed August 11, 1919. Serial No. 316,829.

To all whom it may concern:

Be it known that I, GEORGE C. ANTHON, a citizen of the United States, residing at New York, in the county of New York and State of New York, have invented certain new and useful Improvements in Heat-Insulated Receptacles, of which the following is a specification.

This invention relates to thermally insulated receptacles of the type generally known as vacuum bottles and particularly to those in which the spaced shells of the receptacle are made of metal, such as steel, joined together at the neck of the bottle as by means of welding. This joinder of the inner and outer shells provides in effect a thermal "bridge" between the two shells across which a transfer of heat may take place, and which therefore detracts to a certain extent from the efficiency of the device.

One of the objects of my invention is to reduce so far as possible, these "losses" through the neck or connecting bridge between the two shells; and further to accomplish this result without impairing the physical structure of the vessel or interfering with the securing of the parts together by means of welded joints.

Another object of the invention is to so construct the parts that the inner and outer shell may be held fixed in spaced relation wholly by means of the connection between the neck portions of the two shells.

Accordingly, one feature of the invention consists in the provision of a connecting neck-piece between the inner and outer shells of a material which is of greater thermal resistivity than the material of the shells. In the case of steel shells I find a special alloy of nickel and copper particularly suited for this thermal bridge, and this alloy also is of such a nature that it can be readily welded to the metal of the shells.

Another feature of the invention is the provision of over-lapping telescopic joints between the parts, which joints, by reason of their over-lapping relation, brace the connected parts so that the inner shell may be supported wholly by means of the neck portion between the two shells.

Other features of the invention will appear as the specification proceeds.

In the accompanying drawings I have illustrated in Figures 1 and 2 longitudinal sectional views of practical and preferred

embodiments of my invention, but would have it understood that the structure may be modified in various respects without departure from the spirit and scope of the invention as defined in the appended claims. 60

In these drawings, and in Figure 1 particularly, 1 designates the outer shell and 2 the inner shell, said shells being usually constructed of steel and separated by an intervening heat-insulating space 3 exhausted to the proper degree and containing usually a filling of gas-absorptive material.

4 designates the thermal insulating neck-piece connecting the outer and inner shells, 70 said neck-piece being shown herein as a slightly tapered sleeve fitted telescopically at its upper end in the flanged neck-piece 5 of the outer shell and similarly telescopically engaged at its inner end with the 75 flanged neck portion 6 of the inner shell.

The high thermal resistivity or thermal insulating character of this bridging element between the outer and inner shells is obtained by making said element of a 80 metal which is of low thermal conductivity. At the present time I use an alloy for this purpose of substantially fifty per cent nickel and fifty per cent copper. This alloy answers the purpose of a metallic thermal insulator between the outer and inner shells and also is of such a character that it can be welded to the steel shells. These 85 welded connections are made at the relatively wide over-lapping joints at 5 and 6 90 between the outer and inner shells and the opposite end portions of the neck-piece. In addition to facilitating the formation of good welded joints, the over-lapping telescopic connections described serve to brace 95 the connected parts and cause the inner shell to be firmly supported in spaced relation within the outer shell without the necessity for the braces customarily provided between the bottom portions of the 100 inner and outer shells. And while the over-lapped joints provide an increased surface contact between the shells and the neck-piece, any effect as to increased heat conduction at these joints is more than overcome by the intervening span of higher thermal resistivity between the two shells.

The inner shell is shown made in two parts, the lower body part (indicated at 2) and an upper part 7 of substantially frusto- 110

conical shape. This upper section 7 is also shown connected by means of a telescopic over-lapping joint with the lower body section as indicated at 8, thus carrying forward the bracing effect already referred to.

The outer shell is shown closed at the lower end by inner and outer bottom plates 9 and 10 and a false bottom 11, said parts being suitably secured to the shell as by means of the over-lapped welded joints illustrated. The inner bottom plate 9 is shown formed with a cupped depression 12 in the centre thereof perforated as shown at 13 for the escape of gases during the exhausting process. To prevent exhaustion of the filling material as well a filter 14 of material such as mineral wool may be placed in this pocket. The second bottom plate 10 is shown provided with a central depression or cup 15 providing a chamber about the perforated cup of the first bottom into which opens the exhausting tube 16 which, upon the completion of the exhausting process, is sealed off in any suitable manner.

In the second form of the invention illustrated (Figure 2) the outer shell is formed with an annular shoulder 17 in the neck portion thereof and with an annular enlargement 18 below said shoulder providing a seat in which the outer end of the neck-piece 4 is engaged. Preferably the parts are so proportioned that the inner wall of the neck-piece will be in line with and form a continuation of the inner surface of the neck portion of the outer shell, as indicated. This allows for a smooth flow of the liquid, and the relatively wide overlapping joint at 18 provides a secure connection between the parts and one which is readily welded.

The mouth of the outer shell may be finished off with a bead or rolled-over portion 19 which may stand out far enough to substantially cover the enlarged and shouldered portion of the neck of the outer shell.

These metallic receptacles are usually provided with a non-corrosive lining of suitable material, such as enamel. This enamel adheres readily to the steel shells, but in some cases less readily to the neck-piece which, as above described, is usually constructed of an alloy of higher thermal resistivity than steel. The construction illustrated in Figure 2 is particularly ad-

vantageous in this connection, in that the 55 enamel coating, which extends continuously from the inner shell through the neck-piece to the mouth of the outer shell, is in this case firmly anchored at the opposite ends of the neck-piece, at the points indicated 60 at 20 and 21 to the steel inner and outer shells. The lining is thus permanently secured at the opposite ends of what may be the weakest portion thereof and at the point where the wear comes, that is, at the mouth 65 of the receptacle, the enamel is continued with the steel of the outer shell and with which it forms a permanent and durable connection.

I claim:—

1. A heat insulated receptacle comprising an outer shell having a shouldered neck portion with an annular enlargement below said shoulder forming an annular seat, an inner shell and a connection between said 75 inner and outer shells having its outer end seated in said annular enlargement beneath the shoulder in the neck portion of the outer shell.

2. A heat insulated receptacle comprising 80 an outer shell having a bead at the mouth thereof, a shoulder in the neck portion below said bead and an annular enlargement beneath said shoulder, an inner shell and a neck-piece connecting the inner and outer 85 shells and seated in the annular enlargement aforesaid.

3. A heat insulated receptacle comprising an outer shell having an annular shoulder 90 on the interior of the neck portion thereof, an inner shell and a neck-piece extending from said inner shell and seated in the neck portion of the outer shell substantially in engagement with the shoulder aforesaid.

4. A heat insulated receptacle comprising 95 an outer shell having an internally shouldered neck portion and provided with an annular enlargement beneath said shoulder, an inner shell and a neck-piece connected at its inner end with the inner shell and seated at its outer end in the annular enlargement aforesaid and with its inner surface substantially flush with the inner surface of the neck portion of the outer shell.

In testimony whereof I affix my signature.

GEORGE C. ANTHON.
